COAL FEED TUBE

William S. Anderson, Williamsport, Pa., assignor
of one-half to James E. Axeman, Williams-
port, Pa.

Application November 19, 1949, Serial No. 128,300

3 Claims. (Cl. 198—215)

1

This invention relates to coal feed tubes for furnaces and has for an object the provision of improvements in this art.

An improved type of coal feed tube recently put on the market comprises an interior helicoid or screw and an outer tubular member or casing attached together and rotated as a unit to elevate coal from a bin at a lower level to a furnace feed opening at a higher level.

The helicoid raises the coal particles on one side of the tube and they slide downward by gravity but at a forward angle relative to the axis of the tube so they advance upward. In effect, the particles slide upward. However, the movement is not entirely a sliding action. The particles roll over the surface of the drum or tube and over each other. They are irregular in shape and make a tinkling noise as they fall on the tube surface, the noise being loudest, of course, when particles roll completely across the advancing layer of material and fall on the lower side.

The resultant tinkling noise is objectionable, especially in residences where the installations are commonly used, and more particularly so where it is impractical to sound-proof the entire installation in a separate lined room.

It is therefore an object to eliminate this noise from the coal feed tube.

A related object is to eliminate the noise by the simplest and least expensive possible means.

According to the present invention the coal tube comprises inner and outer tubular members provided with a sound-insulating space therebetween so that the outer tubular member does not convey noise from the inner tube on which the coal travels, the inner surface of the inner tubular member at the same time having such a low coefficient of friction that the coal will continue to move principally by a sliding action without increasing the tumbling action to such an extent that the sound-producing blows are increased.

A soft rubber lining inside the metal tube will stop the tinkling noise but its coefficient of friction is so great that it causes too much tumbling of the coal and wear on the lining, hence is impractical.

Sound insulation alone on the outside of the metal coal tube is found to give a slight improvement but is inadequate for the purpose, apparently because there is no solid barrier on the outside to prevent escape of noise to the air.

2

The construction provided by the present invention has proved to be very effective in service, apparently because, in addition to the high insulating character and low interior coefficient of friction, it also provides an outer solid barrier to the passage of sound from the inside.

The above and other objects and advantages of the invention will be apparent from the following description of a preferred exemplary embodiment which is illustrated in the accompanying drawings, wherein:

Fig. 1 is a side elevation of a coal burning furnace embodying the invention;

Fig. 2 is a partial enlarged elevation cut away in places to show the interior construction;

Fig. 3 is a further enlarged cross section through the coal feed tube; and

Fig. 4 is a magnified cross section of one side of the tube, the view being taken in the circle 4 of Fig. 3.

As shown in the drawings, the furnace installation which provides a setting for the present invention comprises a furnace 10 having a coal feed header 11 and a rotary coal feed tube 12 extending at an angle upward from a coal bin 13 to the header. Intermediate its length, the tube is rotatably supported by a trunnion bearing 14, and adjacent the bearing is provided with a sprocket 15 which is driven through a chain 16 from a motor 17.

Interiorly the tube is provided with a helicoid or spiral fin screw 18 which is maintained in a fixed position relative to and rotates with the tube. The lower end of the helicoid at each turn of the tube picks up a small amount or pocket of coal and feeds this pocket of coal upward by a sliding action with some tumbling, as explained above. Fig. 3 illustrates how the pocket of coal is raised on one side of the tube as the tube rotates and how a particle or lump from A on the upper side rolls across the layer or pocket, as shown at B, and falls on the tube surface on the lower side of the layer, as shown at C. The individual particles tumble separately, and there are various intermediate types of tumbling action, but it is the longest fall, where the lumps strike an open surface of the tube, which causes the greatest tinkling noise.

To eliminate this tinkling noise there is provided a lining which has good sound-proofing and sliding characteristics. The lining may consist of a single layer of a suitable material but preferably comprises two layers, an outer layer 20 which has principally sound-deadening characteristics, for example fiber sheet such as asbes-

tos and many other substances of a similar nature, and an inner layer 21 which has principally good wearing and friction-reducing characteristics, for example sheet metal. Since the wear is not great, the metal sheet may be quite thin, a 28 gauge galvanized sheet metal having been found to give very satisfactory results in service. The outer tube 12 may be and preferably is thicker and stronger, a 16 or 11 gauge galvanized steel sheet metal having been found to provide the necessary strength and rigidity to do the required work. When a metal liner is used it is permissible to use a thinner outside tubular member than would otherwise be suitable. A single thickness of asbestos paper has been found to give good sound-deadening effects when used as the intermediate space filler.

For convenience in manufacture, it is preferable to place the layer of metal 21 and the layer of sound-deadening material 20 around the helicoid 18 and to insert this sub-assembly in the main coal tube 12. The helicoid may be attached at its ends to the coal tube or it may be retained by friction. It is stiff enough to hold its shape between its ends. However, it has some resilience and may be twisted to reduce its diameter before the lining layers 21, 20 are placed thereon so the sub-assembly may be readily inserted in the coal tube 12. Re-expansion of the helicoid causes the sub-assembly to be firmly retained in position within the coal tube.

It will be seen that the inner surface is almost or completely sound-insulated from the outer tube and that the outer solid tube forms a sound barrier so that, consequently, there can be no noticeable passage of sound to the outside, either through the sides of the coal tube to the adjacent air or through its ends to the furnace installation or to the air. Such sounds as may tend to travel through the tube are muffled by the closed arrangement at the ends.

The form illustrated has the heavier solid tube on the outside. It may be on the inside if suitably strong and rigid bearing and drive assemblies are provided for the tube assembly as a whole. The solid tubes are shown to be of considerably different thickness and this is believed to be beneficial because they then have different natural periods of vibration and the outer tube more completely dampens the vibrations and overtones caused by particles falling on the inner tube, but tubes approaching or reaching unity of thickness produce greatly improved quietness over installations which do not have the sound-deadening elements.

While one embodiment has been illustrated and described, it will be understood that there may be various embodiments within the general scope of the invention.

I claim:

1. A feed tube for feeding upward on an incline particles of hard material, such as coal and the like, comprising in combination, an outer metal tube mounted on an incline for rotation, a smooth inner metal tube mounted within and spaced from the outer metal tube, and an integrally continuous spirally wound helicoid sheet metal fin mounted within said inner tube and secured at its ends to the tube assembly to rotate therewith, the fin fitting tightly within said inner tube and being open along its inner longitudinal axis, the inner metal tube being thinner and having a different vibration frequency from the outer metal tube whereby sound vibrations imparted to the thin inner tube by particles striking thereagainst are damped or blanked by the thick outer metal member.

2. A feed tube as set forth in claim 1 which further includes a tubular layer of sound-damping sheet material between the inner and outer metal tubes.

3. A feed tube for feeding upward on an incline particles of hard material, such as coal and the like, comprising in combination, an outer relatively thick-walled metal tube rotatably mounted at an incline in bearing supports, an inner smooth relatively thin-walled metal liner tube mounted therein and spaced therefrom, a relatively thin layer of insulating material between said metal tubes, and an integrally continuous spirally wound helicoidal sheet metal screw feed fin secured only at its ends within said liner tube and tightly held therein along its length by the resilience of reexpansion, the feed fin having such radial width as to leave a central axial opening therein such that particles can fall back over the fins and strike the surface of the inner tube, said inner and outer tubes having thicknesses and periods of vibration sufficiently different to minimize the transmission of sounds past the outer tube to the surrounding medium, the lower end of the feed tube assembly being positioned in a coal bin and the upper end being positioned in an enclosed delivery header of a furnace.

WILLIAM S. ANDERSON.
